UNITED STATES PATENT OFFICE.

ARTHUR R. CURTIS, OF CLEVELAND, OHIO.

GLOVE-CLEANING MACHINE.

1,255,515.

Specification of Letters Patent. Patented Feb. 5, 1918.

Application filed February 19, 1914. Serial No. 819,732.

To all whom it may concern:

Be it known that I, ARTHUR R. CURTIS, a citizen of the United States, and a resident of Cleveland, county of Cuyahoga, State of Ohio, have invented a new and useful Improvement in Glove-Cleaning Machines, of which the following is a specification, the principle of the invention being herein explained and the best mode in which I have 10 contemplated applying that principle, so as to distinguish it from other inventions.

The present improvements relate to cleaning machines adapted for use in cleaning gloves or similar articles in a suitable cleaning solution such as gasoline and liquid soap. In this type of machines the cleaning action is secured by the movement of the articles to be cleaned through the cleaning solution which loosens and softens the dirt on the 15 articles, and by the rubbing of the articles against suitable brushes which are placed in the solution and are mechanically operated in different ways. It is customary to provide one or more fixed brushes in the solution, and to move over these fixed brushes other movable brushes in different ways, although the action of the movable brushes is usually a rotatable one. The difficulty in 20 this method of procedure is that the gloves are formed into balls or wads by the action of the moving brush, subjecting them to injury and preventing thorough cleaning.

In the present invention I have provided a construction which permits of the rapid 25 cleaning of the gloves without injury, and which automatically prevents the rolling of the gloves into large masses, thus preventing injury to the same. In addition to this feature, I have provided means which permit of convenient removal of the gloves 30 when cleaned and of the brushes for cleaning the latter. Other means have been provided which permit of an adjustment of the pressure of the brushes upon the gloves, 35 which should of course be varied according to the type of gloves being cleaned and to the number of gloves in the machine. To the accomplishment of the foregoing and related ends, said invention, then, consists of 40 the means hereinafter fully described and particularly pointed out in the claims.

The annexed drawings and the following description set forth in detail certain mechanism embodying the invention, such dis-

closed means constituting, however, but one 55 of various mechanical forms in which the principle of the invention may be used.

In said annexed drawings:—

Figure 1 is a side elevation of the machine having the casing partially cut away 60 to show the brushes; Fig. 2 is a top plan view of the casing with the upper brush removed, a portion of the casing being cut away to show the driving connections; Fig. 3 is a central vertical section through the 65 machine; Fig. 4 is a side elevation of a portion of the two brushes showing the action of the same on the gloves; Fig. 5 is a partial side elevation showing the method of removal of the fixed brush by means of an 70 improved tool, which I have provided for the purpose; Figs. 6 and 7 are partial side elevations illustrating slightly modified types of brushes which may be used; and Fig. 8 is a section on the line 8—8 in Fig. 3. 75

In Fig. 1 there is shown a suitable stand or support 1 upon which is mounted a casing 2, preferably of cylindrical form, and vertically disposed, such casing being open at its upper end and being provided centrally in its lower end with an aperture 3. Upon the closed end 4 of the casing about such aperture there is mounted an upstanding flange 5 disposed concentrically within the walls of the cylinder and extending to 80 substantially the same level as the top of the same, thus forming an annular space between the sides of the cylinder 2 and the flange 5.

Supported upon the rim of the circular 90 flange 5 is a centrally apertured cover plate 45 having a depending flange 46, said cover plate forming a bearing for a rotatably mounted hollow shaft 47 which is similarly mounted at its lower end in a second bearing 95 formed by a flange 48 on a bottom cover plate 49. Attached to said hollow shaft are two spaced shoulders 10, the shaft being hollow between such shoulders. Removably mounted upon the upper end of the rod 6 is 100 a frame 50 having radially and downwardly extending arms 7 attached to a brush 8 which is disposed horizontally, being provided on its lower surface with suitable bristles 9. The frame 50 bearing said brush 105 has two apertures disposed to fit snugly and slidably over such shoulders 10, thus locking said frame 50 non-rotatably to said hol-

low shaft 47. The driving of the frame 50 (and the upper brush) is accomplished from the hollow shaft 47 while the raising action is secured solely by means of the reciprocating rod 6.

It will be noticed that the brush 8 is fitted snugly and slidably about the flange 5, thus insuring that this brush is maintained in its horizontal position when being raised. This 10 is further secured by the length of the shoulders 10 which serve as additional bearings for the frame 50 to which is attached the brush 8.

The brush 8 fits slidably between the inner and outer walls of the cylinder and is made up of a plurality of segmental portions 11 which are disposed as shown in Fig. 2, thus forming an annular brush, the adjacent portions being slightly spaced to 20 provide slots or openings 12 between the same. The segmental portions are maintained in such relation by means of annular ribs or rings 13 of which there are two, one placed adjacent the outer edge of the assembled brush, and the other adjacent the inner edge.

On the bottom of the casing there are mounted a plurality of lugs 14, preferably three, and upon the bottom there is placed a 30 second brush 15 which may be termed a fixed brush, as it does not move, although it is removable and is held in position merely by the engagements of the lugs 14 in the slots 12 formed in the brush, this second brush being constructed as is the brush 8 already described, being made up of segmental portions 11 held together by means of annular rings 13. The shaft 47 is adapted to be oscillated by means of an arm 16 pivotally attached to the shaft at a point 35 slightly below the bottom of the casing, the other end of such arm being eccentrically attached to a disk 17, such disk 17 being driven by a pulley 18 attached thereto and operated from any suitable source of power. The rod 6 is disposed in a substantially vertical position in the shaft 47 and is reciprocably mounted, its lower end 19 being pivotally attached to a link 20 which is slidably 45 mounted over a horizontal cross-bar 21 forming one of the cross-bars of the base or support 1.

A foot-lever 22 is pivotally mounted upon a stud 23 projecting from another of the 55 cross-bars of the base, the stud being parallel with the cross-bar 21 to which the link 20 is slidably connected. This foot lever 22 is pivotally connected at its outer end to the link 20 at a point intermediate the previously mentioned points of attachment of the latter. By moving the outer end of the 60 foot lever 22 from the position shown in full lines (Fig. 1) to the position shown in dotted lines, the rod 6 is raised substantially vertically, although there is a slight oscillation

of the same, thus raising up the frame carrying the upper of the two brushes 8 until it is above the top of the casing. The latter is normally closed by a suitable cover 24 which is removably mounted thereon. It 70 will be evident that the cover 24 is so constructed and positioned that it will be contacted by the upper brush 8 when being lifted, the further movement of such brush raising the cover from the casing. This 75 operation is secured by a pressure of the operator's foot upon the pedal 22, thus leaving his hands unengaged, so that he can reach into the casing and collect and remove the gloves therein. This is by far the most 80 convenient arrangement in this particular and one made possible by the construction already described. The latter may be held in such raised position by means of a pawl 26 engaging a notched bar 27 mounted upon 85 the base, the pawl being pivotally attached to the foot lever 22 as indicated. When the cover 24 and the upper brush are in such raised position, it is possible to conveniently reach in and remove the gloves which will 90 be found lying upon the lower brush. This can be done very easily without entirely removing the cover and the upper brush from the shaft, as there is a sufficient space between the edge of this brush and the top of 95 the cylindrical casing.

It is not always sufficient in a cleaning machine of this type to merely provide two brushes, one fixed and the other oscillatory, for cleaning the gloves, as such a construction does not prevent the rolling up of the gloves into balls during the operation. I have found that a simple method of preventing any such balling of the gloves consists in mounting the bristles 9 in the upper or oscillatory brush at an acute angle to one of the directions of movement of said brush. Thus it will be seen from Figs. 1 and 4 that the bristles 9 in the lower or fixed brush 15 are mounted in the usual manner at right angles 100 to the surface of the brush, although they may be inclined slightly to the left, while the bristles in the upper brush are mounted at a slight angle, preferably about 60°, to the direction of movement of said brush during one of its oscillatory movements. The action which is thus secured may be described as follows, reference being had to Fig. 4. If it is assumed that a certain bunching action has taken place among the 105 gloves disposed between the brushes, and that a bunch 30 of substantially the same size as that shown in Fig. 4 has been formed, it will be seen that upon movement of the brush in the direction indicated by the arrow 110 in Fig. 4, the bristles 9 in the upper brush 8 will have but a slight "feeding" action upon the gloves in this bunch, since the bristles are inclined sufficiently to drag over the gloves 115 and not to engage the same with any force. 130

Upon the movement of the brush in the opposite direction, each bristle in the upper brush engages the top glove of such bunch with a certain resilient force secured by the 5 positioning of the bristles at this angle. During the movement in this direction the uppermost gloves in the bunch are successively moved off of the same into the space next to the bunch, thus distributing the 10 gloves and preventing any increase in the size of the bunch. Upon the return of the brush after such action the gloves are not brought back into the bunch, since the bristles have less effective force in moving the 15 gloves. In this way any bunches that may form between the brushes are continuously broken up by the oscillation of the brush having bristles disposed in the manner described.

20 It must be understood that while I have here used the word "bunch" for convenience, I mean by this word in the present connection not the tightly rolled ball of gloves to be found in most machines of this character, 25 but merely what may better be termed a congested portion of the entire number of gloves in the casing. In the present invention the constant differential feeding action serves to prevent the formation of an actual 30 bunch although the gloves do tend to congregate at some points and leave other spaces substantially free from gloves. By the feeding action of the brushes these dense areas are thinned by the scattering of the upper 35 most gloves and this prevents the formation of any actual "bunch", as the term is understood in the trade. The bunch shown in Fig. 4 is of course exaggerated for the purpose of illustrating the brush feeding action, 40 as no bunch of this size can be formed in the present machine.

In Fig. 6 I show an upper brush having bristles standing at a slightly different angle than that of the bristles in the previous figures, it being a matter of indifference as to the precise angle at which they are set. Similarly, the bristles in the lower brush may be inclined slightly as indicated in Fig. 7 and if they are sufficiently inclined the 50 bristles in the upper brush may be straight or nearly so, the feeding action being secured by the inclined bristles in the lower brush. For practical reasons I prefer the bristle arrangement shown in Figs. 1 and 4, in which 55 the bristles of the upper brush are inclined while those of the lower brush are straight. The lint and dirt settle mostly in the lower brush and it is much easier to clean the same when the bristles are at right angles to the 60 brush surface, thus making this the type to be preferred under ordinary conditions.

65 It is obvious that a pressure between the brushes which is suitable for one type of material is too great or too little for other softer or tougher materials, and it is desirable that

means of adjustment for this pressure be provided. Normally the weight of the upper brush 8, together with the frame to which it is attached, is sufficient for cleaning purposes, this weight being lessened by the 70 buoyancy of the upper brush which is of course operating beneath the surface of the cleaning liquid. Additional weight may be given to the brush, and hence an additional pressure be put on the gloves, by placing 75 weights 31 upon the top of the frame which engages between the shoulders 10 formed on the oscillatory shaft 47, such weights being formed as shown in Figs. 1 and 3. A sufficient number of weights may be added to 80 give practically any desired pressure upon the gloves. I provide means for lessening the normal pressure due to the weight of the upper brush upon the gloves by providing a frame or weight-receiving platform 85 32 upon the outer end of the foot lever 22 upon which may be placed the same weights 31 that are used upon the frame attached to the upper brush. The placing of weights 31 upon the outer end of the foot lever tends 90 to raise the rod 6 and will raise the same when the effective force of these weights equals the weight of the upper brush plus the weight of the shaft. When equilibrium is reached the upper brush will merely float 95 in the cleaning solution and will exert practically no pressure upon the gloves therein. It is sometimes desirable to relieve all the weight of the upper brush and to permit it to float in the solution near the top of the 100 same. In this way a gentle cleaning action is secured, the gloves moving about in the solution and rubbing against the brushes but without great pressure, as is desirable with certain classes of gloves.

105 Considerable trouble has been met with in cleaning machines of this type by reason of the large amount of lint which is removed from the gloves by the cleaning action. This lint settles at the base of the bristles and after a considerable time clogs up the brush so that it exerts practically no cleaning action. It is necessary, in order to keep the brushes clean to remove the same at frequent intervals and to then pick out what lint is 110 embedded at the base of the bristles, and it is for this purpose principally that each of the two brushes have been made removable. The construction of the upper brush has also been designed with a view to removing as 115 much as possible of this lint by the mere action of raising the upper brush from the liquid. The cleaning solution stands several inches above the top of the upper brush 8, and if the latter is pulled quickly out of 120 the casing 2 through the solution the latter would normally tend to run down over the outer edge of this brush. By constructing the brush in segments 11 and by leaving 125 spaces or slots 12 between each two segments 130

I provide numerous passages for the escape of the liquid during the raising of the brush. I prevent the escape of the liquid over the outer and inner edges of the brush by the 5 annular rings 13 placed adjacent to each edge, thus forcing the liquid to pass downward through the slots, which action removes a considerable part of the lint which has been deposited in the bristles adjacent 10 thereto. The bristles are so disposed that a continuous surface is presented as will be evident from Figs. 2 and 3. The bristles adjacent to the slots are spaced slightly differently from those at other points and the 15 bristles on the edge of the slots are inclined at a slightly greater angle in order to form a substantially uniform brush surface. This cleaning action is made possible by the suction produced on the lower surface of the 20 brush when it is drawn rapidly up through the solution. In practice it is best to move the brush upward until near the top of the solution and then pause momentarily, to allow the solution on top of the brush to drain 25 off through the slots.

The lower brush may be cleaned in the same manner by means of the tool 40 shown in Fig. 5. Two of these tools are passed down in the slots 12 in the fixed brush 8 30 where they engage beneath the annular rings 13, thus permitting the fixed brush to be raised until out of the cleaning solution. It is then reversed and moved through the cleaning solution several times in order to 35 separate out as much of the lint as is possible in the same way that the upper brush is acted upon.

In using annular disk brushes of the present type it is essential to successful operation 40 that a certain minimum movement be given to each portion of the brush. The reason for this can best be shown by an explanation of the action of the brushes on a single glove placed therebetween. Upon the first movement of the brush, the glove is rolled up on 45 itself to some extent, the fingers being rolled up on the palm or the like. It is essential that the moving brush have a greater movement than is necessary to merely produce 50 this rolling movement of the glove, as otherwise the glove is given no movement over the fixed brush.

The several features of the machine to which I call particular attention are the disposition and construction of the driving 55 mechanism which is so arranged that the machine may be readily opened for purposes of inspection and cleaning, and the construction of the brushes and the movement given 60 to the same which features combine to afford convenient efficient operation.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In a glove cleaning machine, the combination with a casing adapted to contain a cleaning solution; of two annular disk brushes mounted in said casing in a parallel relation, one of said brushes being oscillatory 75 with respect to the other, and one of said two brushes having bristles inclined at less than right angles to the plane of said brush, such inclined bristles being operated, upon oscillation of said oscillatory brush, to resili- 80 ently feed the material placed between said brushes in one direction; and means adapted to cause oscillatory movement of one of said brushes with respect to the other.

2. In a glove cleaning machine, the combination with an annular casing adapted to contain a cleaning solution; of an annular disk brush mounted in said casing; a second disk brush oscillatorily mounted opposite said first-named brush and having bristles 90 inclined to the plane of the same; means adapted to oscillate said last-named brush; the distance through which the innermost portion of said oscillatorily mounted brush travels being greater than the travel suffi- 95 cient to produce a rolling action on gloves placed between said brushes.

3. In a glove cleaning machine, the combination with a cylindrical casing open at one end and provided with a central aperture in its closed end; a flange mounted about such aperture within said casing; a brush mounted upon the closed end of said casing; an operating shaft extending within said flange through such aperture; and a second 100 brush removably mounted on, and driven by, said shaft, said last-named brush being within said casing.

4. In a glove cleaning machine, the combination with a cylindrical casing open at one 110 end and provided with a central aperture in its closed end; a flange mounted about such aperture within said casing; a brush removably mounted upon the closed end of said casing; an oscillatory shaft extending within said flange through such aperture; a second brush removably mounted on, and driven by, said shaft, said last-named brush being within said casing; and means adapted to 115 variously position said second brush vertically.

5. In a glove cleaning machine, the combination of a cylindrical casing open at one end and provided with a central aperture in its closed end; a flange mounted about such aperture within said casing; a brush mounted upon the closed end of said casing; an oscillatorily mounted hollow shaft disposed within said flange; a second brush removably mounted on, and driven by, said shaft; a rod 120

reciprocably mounted within said shaft and bearing said second brush; and means adapted to reciprocate said rod, thereby raising said second brush away from said first-named brush.

6. In a glove cleaning machine, the combination of a vertically disposed, cylindrical casing open at its upper end and provided with a central aperture in its lower, closed end; a flange mounted about such aperture within said casing; a brush mounted upon the closed end of said casing; an oscillatorily mounted hollow shaft extending within such aperture; a second brush normally resting upon, and supported and driven by, said shaft; the weight of said brush maintaining the same against the gloves disposed upon said first-named brush with a certain amount of pressure; a rod reciprocably mounted within said shaft and adapted, when raised, to contact and lift said second brush from off said shaft; a pivotally mounted lever connected to said rod, and adapted, when operated, to raise the same; said lever being provided with a weight receiving platform, the addition of weights to said lever tending to raise said rod and said brush and decreasing the pressure of the latter against the gloves upon said first-named brush.

7. In a glove cleaning machine, the combination of a vertically disposed, cylindrical casing open at its upper end and provided with a central aperture in its lower, closed end; a flange mounted about such aperture within said casing; a brush mounted upon the closed end of said casing; an oscillatorily mounted hollow shaft extending within such aperture; a second brush normally resting upon, and supported and driven by, said shaft; the weight of said brush maintaining the same against the gloves disposed upon said first-named brush with a certain amount of pressure; a rod reciprocably mounted within said shaft and adapted, when raised, to contact and lift said second brush from off said shaft; a pivotally mounted lever connected to said rod, and adapted, when operated, to raise the same; said lever being provided with a weight receiving platform, the addition of weights to said lever tending to raise said rod and said brush and decreasing the pressure of the latter against the gloves upon said first-named brush; and said second brush also being provided with a weight-receiving platform, the addition of weights to said brush increasing the pressure of the lat-

ter against the gloves upon said first-named brush.

8. In a glove cleaning machine, the combination of a casing open at one end and provided with a central aperture in its closed end; a flange mounted within said casing about such aperture; a shaft extending through said flange; a second brush slidably but non-rotatably supported upon said shaft, said brush fitting snugly but slidably around the outer wall of said flange in said casing in order to maintain said second brush in such parallel relation during such movement; and means adapted to reciprocate said second brush and to thereupon support the same, raising said brush from off said shaft.

9. In a glove cleaning machine, the combination of a cylindrical casing open at one end and provided with a central aperture in its closed end; a flange mounted about such aperture within said casing; a brush mounted upon the closed end of said casing; a rod reciprocably mounted within said flange; a second brush mounted in said casing above said first-named brush; means adapted to normally support said brush and to operate the same; and other means connected to said rod and adapted to reciprocate the same, said rod thereupon contacting said second brush and raising the same from off said first-named means.

10. In a glove cleaning machine, the combination of a casing adapted to contain a cleaning solution; a brush fixedly mounted upon the bottom of said casing; a second brush reciprocably mounted above said first-named brush and being provided with radially arranged drainage slots and annular guide rails to direct the cleaning solution through such drainage slots when said second-named brush is raised.

11. In a glove cleaning machine, the combination of an open casing adapted to contain a cleaning solution, a cover closing the open portion of said casing, a brush fixedly mounted in said casing, a second brush co-operatively mounted with respect to said fixed brush; and means for separating said brushes and simultaneously raising said cover.

Signed by me, this 17th day of February, 1914.

ARTHUR R. CURTIS.
